CLAIM

The ornamental design for a corner for an electric razor, as shown and described.

DESCRIPTION

FIG. 1 is a bottom, front and right end perspective view showing my new design;

FIG. 2 is a front view thereof;

FIG. 3 is a bottom view;

FIG. 4 is a right end view thereof;

FIG. 5 is an inverted rear view thereof;

FIG. 6 is a left end view thereof; and,

FIG. 7 is a top view.

The broken line showing of the electric razor is for illustrative purposes only and forms no part of the claim design.
